UNITED STATES PATENT OFFICE

RICHARD CONOVER, OF CINCINNATI, OHIO, ASSIGNOR TO THE CROSLEY RADIO CORPORATION, OF CINCINNATI, OHIO, A CORPORATION OF OHIO

LOUD-SPEAKER MOTOR

Application filed July 16, 1928. Serial No. 293,028.

My invention relates to motors for loud speakers particularly to the design of the same so as to obtain a balanced armature and reduce to a minimum all parts which will develop periods of resonance during operation of the motor that might result in a distortion of the sounds reproduced therefrom.

It is my object to provide for a structure of loud speaker motor in which accuracy of size and fitting of parts is largely eliminated, as well as rattling joints and complication of assembly. It is my object to cut down the number of different parts used in such a structure, and simplify the erection thereof.

15 A further one of my objects is to provide a motor which is compact and strong, and from which the motion is so directed as to permit of mounting the entire motor within the solid angle of a sound producing cone 20 diaphragm.

These objects and other advantages to be noted I accomplish by that certain construction and arrangement of parts to be herein-after more specifically pointed out and 25 claimed.

In the drawings:

Figure 1 is a plan view of the motor.

Figure 2 is a front elevation thereof.

Figure 3 is a side elevation thereof.

30 Figure 4 is a perspective of the magnet.

Figure 5 is a perspective of one of the pole shoes.

Figure 6 is a plan view of one of the coil spools.

35 Figure 7 is a side elevation of Figure 6.

Figure 8 is a perspective of the armature and the restoring spring therefor.

Figure 9 is a detail of the driving rod or pin.

40 Figure 10 is a perspective of one of the pole spacers.

The motor is built upon a horseshoe shaped magnet, as a preferred form of magnet, as shown at 1, on the tips of which are mounted 45 the pole spacers. These pieces are formed of conductive metal, preferably square rod which is cut to shape in a press, and having main bodies 2, and projections 3.

The spacers are mounted on the ends of the 50 magnet by means of bolts 4 passing through

holes 4a in the magnet tips, and holes 4b in the spacer blocks. The holes 4a are larger than the bolts, thus permitting an adjustment during assembly.

The main bodies are provided with holes 5, 55 for mounting of the pole shoes on each face of the said blocks, and the projections 3, are provided with holes 6, for mounting the coil spools and the armature restoring spring. The result of the use of these spacer blocks is to apply the flux to the armature at right angles to the plane of the ends of the magnet tips, thus reducing the over all space occupied by the motor and enabling me to mount it within the solid angle of a conical diaphragm 65 of normal size.

The pole shoes are made of pieces of plate metal 7, with slanting rear faces 8, all of the shoes being the same. (Fig. 5.) The shoes are arranged in pairs on the two side faces 70 of the pole spacers as indicated best in Fig. 1 and are held in place by the four bolts 5a, which engage in the holes 5 in the spacer blocks.

The pole shoes are mounted in place after 75 the rest of the motor has been assembled and mounted on the pole spacer projections.

I provide a pair of spools 9, (Figs. 6 and 7), having projections or ears 10 projecting from one of the heads of each spool and a 80 terminal lug 11 projecting from the other spool head at other than right angles to the ears so that when the spools are assembled with the faces having the two ears thereon in juxtaposition, the terminal lugs will not 85 entirely overlap each other (Fig. 1).

The armature is in the form of a bar of silicon steel or other proper metal, as indicated at 12, and is held at its center or approximately so, within a spring strip 13. 90 This strip has two mounting ears 14 at its ends. The armature has a phosphor bronze rod or driving pin 15 soldered or welded to one of its ends, the other end being left free.

In assembling the device, after the pole 95 spacers are bolted into place the one spool is set onto the projections of the spacers with its attaching ears registering with the holes 6. The armature spring is next set in place with its ears registering with the ears on the 100

one spool. The second spool is then set in place over the armature spring, and then the two bolts 16 are employed to bolt the assembly of parts down fast to the projections of the spacer blocks.

5 The pole shoes are then mounted in place, as has been described and the structure is completed except for attaching the wires which conduct the audio frequency current from whatever receiver is used, to the two spools.

10 The armature is tipped at its ends as a result of the flux set up by the winding on the two spools, through the center of which spools the armature passes, and the restoring spring 15 operates as a torsion spring to maintain the armature in a central position.

15 There is no pivotal linkage between the armature and the diaphragm, which is to be connected direct to the end of the drive rod. The parts can be rapidly and accurately assembled, and all parts are tightly bolted in place, with a minimum of bolts, and in a very compact manner.

20 25 The whole structure presents a balanced armature type of loud speaker motor, which operates very effectively with a minimum of self generated resonance.

Having thus described my invention, what 30 I claim as new and desire to secure by Letters Patent is:

1. In a loud speaker motor, the combination of a magnet, pole spacers thereon having projections, an armature restoring spring 35 mounted on the projections, said spring having secured thereto an armature, coils set around the armature at both sides of the restoring spring, and pole shoes mounted on the pole spacers in opposed pairs with their 40 tips adjacent the said armature.

2. In a loud speaker motor the combination of a horse shoe magnet, blocks mounted on the sides of the tips thereof, an armature and a restoring spring therefor mounted on the blocks so that the armature extends parallel to the legs of the horseshoe magnet, coils 45 for the armature mounted on said blocks, and pole pieces mounted on said blocks in pairs for each end of the armature.

50 3. In a loud speaker motor the combination with the legs of a magnet of pole spacers mounted thereon and having lateral projections, pole shoes mounted on the blocks, coil spools having mounting ears, an armature restoring spring having mounting ears and 55 means for securing the spools with the armature restoring spring between them, and the armature extending through the spools, by the same attaching means to the projections 60 from the pole shoes.

4. In a loud speaker motor the combination with the legs of a magnet of pole spacers mounted thereon and having lateral projections, pole shoes mounted on the blocks, coil 65 spools having mounting ears, an armature

restoring spring having mounting ears and means for securing the spools with the armature restoring spring between them, and the armature extending through the spools, by the same attaching means to the projections 70 from the pole shoes, and pole shoes mounted on the pole spacers in pairs, one on each side of the both ends of the armature, said pole shoes being mounted on the spacer blocks.

5. In a loud speaker motor the combination 75 with the legs of a magnet of pole spacers mounted thereon and having lateral projections, pole shoes mounted on the blocks, coil spools having mounting ears, an armature restoring spring having mounting ears and 80 means for securing the spools with the armature restoring spring between them, and the armature extending through the spools, by the same attaching means to the projections 85 from the pole shoes, and pole shoes mounted on the pole spacers in pairs, one on each side of the both ends of the armature, said pole shoes being mounted on the spacer blocks, and being formed of flat pieces, having their edges in magnetic relation to the said 90 armature.

6. In a loud speaker motor, the combination 95 with a magnet, pole spacers thereon, a pair of spools for armature coils, having attaching ears, and armature restoring spring with an armature extending at right angles thereto, said spring having attaching ears to match those on the coils, and common means for attaching the coils and spring to the pole 100 spacers.

7. In a loud speaker motor, the combination with a magnet, pole spacers thereon, a pair of spools for armature coils, having attaching ears, and armature restoring spring with an armature extending at right angles thereto, said spring having attaching ears to match those on the coils, and common means for attaching the coils and spring to the pole spacers, said spools being alike in shape, and having the said ears on one head thereof, and terminal lugs on the other head, said terminal lugs extending at other than right angles to the ears, whereby in the assembly the lugs 105 will not entirely overlap each other.

8. In a loud speaker motor, a magnet, pole 110 spacers on the magnet, coils and an armature mounted on said pole spacers so that the axis of the coils extends parallel with the faces of the magnet on which the pole spacers are mounted, and pole shoes mounted on the side 115 faces of the pole spacers, and a torsion spring for the armature located between the coils.

9. In a loud speaker motor, the combination 120 with a magnet, means thereon presenting a pair of supports, and a pair of coil spools having ears, together with an armature restoring spring having matching ears and located between the spools, the whole assembly held fast to said supports by common 125 means.

10. In a loud speaker motor, the combination with a magnet, means thereon presenting a pair of supports, and a pair of coil spools having ears, together with an armature restoring spring having matching ears and located between the spools, the whole assembly held fast to said supports by means of screws passing through said ears, and engaging in said supports.
- 10 11. In a loud speaker motor, the combination with a magnet, means thereon presenting a pair of supports, and a pair of coil spools having ears, together with an armature restoring spring having matching ears and located
- 15 between the spools, the whole assembly held fast to said supports by common means, and terminal lugs located on said spools on the opposite heads thereof, to the attaching ears.
